LOOM STOP MOTION

William Harries, Emmaus, Pa.

Filed Mar. 31, 1959, Ser. No. 803,187

3 Claims. (Cl. 139—370)

This invention relates to looms and more particularly to a stop motion adapted to stop the loom when the thread in the shuttle breaks or when the shuttle is empty. The invention is particularly adapted to looms for weaving relatively narrow fabrics or ribbon but is not limited to such materials. In practice these fabrics must be of minimum length, and in many applications the fabric is worthless if it is not of a satisfactory length. If, therefore, the thread in the shuttle should break or run out, the entire piece that has been woven may be useless.

In the past it has been customary to place drop wires on the warp threads to stop the loom in the event of a breakage of the warp threads. However, a counter has been generally relied on to control the woof or fill thread.

An object of the invention is to provide an automatic stop in the event that the quill or shuttle thread breaks or runs out so that the weaver may replace the quill or mend the thread before any damage is done.

In the type of loom in question the warp threads are fed through a reed to the shuttle which reciprocates laterally to weave the shuttle thread into the warp. As the warp threads come through the reed they form a screen. Through the action of the batten the screen of warp threads is pushed rearwardly against the reed by the pressure of the screen and the finished fabric.

It will be understood that the type of loom under discussion is a narrow fabric loom of the general type described in Patent No. 2,470,527, issued to S. F. Siciliano on May 17, 1949, in which the batten reciprocates in and out as the shuttle moves at right angles thereto. With each movement of the shuttle the weft thread is fed by the shuttle through the warp threads and forms an additional piece of fabric. The most forwardly position of the batten is known as the "beat-up," at which position the reed is pressed against the filling thread previously laid. Accordingly, there is pressure against the reed at this point to press it rearwardly.

Other objects and advantages of the invention will be apparent from the accompanying drawings in which—

Fig. 1 is a front view showing a pair of shuttles in position.

Fig. 2 is a sectional view showing the batten in a rearwardly position.

Fig. 3 is a sectional view showing the batten in the forward position.

Fig. 4 is a view of a circuit controlling the stop motion.

This application is a continuation-in-part of my application Serial No. 592,303, filed on June 19, 1956, now abandoned.

Referring more particularly to the drawings, the shuttle 10 is mounted on a batten 11. The shuttle 10 is caused to move laterally by means of the gears 12 while the batten is moved forwardly and rearwardly on the pivoted arm 14. The warp threads 15 and 16 are fed through a screen 17 and when the batten is in the rearward position the shuttle 10 passes through the warp threads to form the fabric 18. The threads are then reversed as the batten 11 is moved forwardly and the weaving continues.

2

In my structure I provide a pivoted or movable reed arm 20 which is urged by means of a spring 21 against a contact member 22. When the batten is in the rearwardly position, as shown in Fig. 2, the end 23 of the arm 20 is in contact with the contact 22. However, the circuit employed provides a micro-switch 25 operated by the adjustable finger 26 on the arm 14. When the batten is in the rearward position, as shown in Fig. 2, finger 26 is out of contact with the micro-switch 25 and the circuit controlling the stop motion is broken. When the batten moves to the forward position, as shown in Fig. 3, the finger 26 contacts the micro-switch 25 to close the circuit. At the same time the woven fabric 18 will contact the arm 20 to position the end thereof, 23, away from the contact 22, thus breaking the circuit controlling the stop motion.

It will be appreciated that in the actual operation of the loom this takes place very rapidly and when one contact is made the other is broken simultaneously as long as the weft thread is fed into the warp. If, however, there should be a break in the weft thread, or if the shuttle is empty, the fabric will not press back the arm 20, and the circuit will be closed, activating the stop motion and stopping the loom.

In order to prevent excessive voltage in the loom, a transformer 30 is provided between the source of current 31 and the rest of the circuit, thus reducing the circuit from 220 volts to 6. The wire 33 runs from the transformer to the micro-switch 25, and the wire 34 runs from the micro-switch to the contact 22. These are all connected to the electrically operated stop motion 35.

I claim:

1. A stop mechanism for looms using a reciprocating shuttle carrying a filling thread and a movable reed for warp threads, a batten mounting both the reed and the shuttle, an electrical contact between the reed and the batten, a spring urging the reed forwardly to close said contact, said reed normally being held out of contact by the pressure of the material being woven, but closing the contact when the shuttle thread is broken or exhausted and the pressure exerted on the reed released.

2. A stop mechanism for looms including a reciprocating shuttle carrying a filling thread, a movable reed, means to supply warp threads through said reed, a batten mounting both the reed and the shuttle, an electrical contact between the reed and the batten, a spring urging the reed forwardly to close said contact, said reed normally being held out of contact by the pressure of the screen of the warp threads and the material being woven but closing the contact when the shuttle thread is broken or exhausted and the pressure exerted on the reed is released.

3. In a loom having a batten and a reciprocating shuttle carrying a filling thread, a movable reed, means to supply warp threads through said reed, a stop motion for said loom, said stop motion being controlled by a circuit, said circuit being energized when the batten is in the beat-up position, an electrical contact between said reed and said batten, a spring urging the reed forward to close said contact, said reed being held out of contact by the pressure of the screen of the material being woven when the batten is in the beat-up position, but closing said contact when the shuttle thread is broken or exhausted and the reed does not contact the woven material.
